TRACK LUBRICATOR

Application filed July 16, 1927. Serial No. 206,296.

Our invention relates to the art of rail-way-track lubrication. Its object is to apply a lubricant to the flange or gauge side of rail head to reduce friction and wear, especially on curved track.

It consists, briefly stated, in a structure comprising a lubricant reservoir; means operable by the wheels of the rolling stock for feeding the lubricant from the reservoir; and a nozzle member for directing the lubricant upon the desired surface.

It also consists in the novel construction and arrangement of the track lubricator as we shall hereinafter fully describe.

In the accompanying drawings, we show our track lubricator in its preferred and modified forms, it being understood that changes may be made therein, without departing from the spirit of the invention, as defined by the claims hereunto appended.

In the drawings—

Fig. 1 is a cross-section of our track-lubricator, showing it applied to the rail.

Fig. 2 is a top plan of the same, the track-rail being omitted.

Fig. 3 is a side elevation of the same taken from the nozzle side, the rail being omitted.

Fig. 4 is a cross section of a modified form of the device, showing it applied to a girder rail.

Referring to Figs. 1, 2 and 3, 1 is a chambered body-member inclosing a reservoir 2, of suitable capacity, for containing a lubricant, access to said reservoir being provided by a hinged lid 3.

One side of the body member is fashioned, as at 4, with a contour conforming to and adapted to seat within the space on one side of the rail 5, bounded by the rail head 6, web 7 and base 8, as seen in Fig. 1; and said side 4 is fitted with a bolt 9 which passes through the rail web 7 and receives a nut 10 upon its end.

11 is a nozzle-member, shaped on its inner face to conform to the surfaces of the rail head, web and base against which it is seated by a bushing 12 encircling the bolt 9 and set up by the nut 10, with intervening spring washers 10^a. Thus the device is fitted to the rail by simple and effective means, though it

will be understood that other forms of connection may be used.

Within the reservoir chamber 2 of the body member 1 is formed a guide member 13 in which the head 14 of the plunger 15 is fitted for reciprocation. The head 14 is offset at 14^a forming a shoulder which lies under the rail head 6, and said head is grooved down from said shoulder at 14^b to receive a stop pin 16 seated in the side 4 of the body member. The shoulder 14^a and the pin 16 form stops to define the upward limit of the plunger stroke, which limit is one which, as shown, presents the plunger head 14 which projects through the top of the body member 1, in a plane slightly above the tread surface of the rail 5 and directly in the path of the overlapping outer portion of the tread 17 of the wheel 18 of the rolling stock, said wheel having the flange 19 on the opposite or gauge side of the rail head.

A spring 20 within the guide member 13 normally holds the plunger in elevated position and returns it thereto after relief from the pressure of the passing wheel. The plunger 15 passes through the bottom of the guide member 13, and is aligned with an open depression constituting a charging pot 21 formed in the bottom of the body member 1, the stroke of the plunger being such as to cause its lower end to enter into and to withdraw from said pot with a close sliding fit.

Suitable ducts lead from the charging pot 21 to the nozzle member 11. For example, as shown in Fig. 1, there is a duct 22 from the bottom of the pot 21; a second duct 23, at the end of the bolt 9 leading upward to the level of the axis of said bolt; another duct 9^a in the axis of the bolt; radial ducts 24 and 24^a in the bolt and the bushing 12, respectively, leading to a peripheral channel 25 in said bushing; and a delivery duct 11^a in the nozzle member 11 with which said channel 25 communicates. A check valve 23^a may be placed, if desired, at any suitable point or points in the duct system. The delivery duct 11^a opens out at a point which enables it to eject the lubricant upon the surfaces desired. It may deliver primarily

upon the side of the rail head 6 or upon the inner face of the wheel flange 19, or upon both said surfaces.

We prefer to deliver the lubricant to surface of the gauge side of the rail head, and to direct and control its initial discharge by a shield plate 26, so that the lubricant will have no tendency to unduly spread either upon the wheel tread or extend to the tread 10 of the rail head.

In the lower portion of the guide member 13 is made a by-pass 13^a, which leads from the duct 23 back into the reservoir 2, crossing the path of the plunger 15. A port 15^a 15 in said plunger controls this by-pass, keeping it closed when out of register therewith and opening it when in alignment, so that a pre-determined charge of lubricant will be forced from the charging pot 21 regardless 20 of any variation in the stroke of the plunger.

In order to protect the plunger head 14 from possible damage a guard plate 27 is provided. This plate is carried by springs 28 to which its ends are secured, the springs 25 being bolted to lugs 29, on the ends of the body member 1, Fig. 3. The guard plate 27 extends over the body member in line with and about at the same level as the plunger head 14, said head being exposed and playing through a hole 27^a in said plate. The guard plate 27 receives the first pressure of the wheel tread as it rides up thereon and yielding thereunder, the wheel passes down the plunger without side impact shock.

35 This guard is particularly useful in making the track safe for the operation of track motor cars. In order to insure the position of the guard plate 27, it is provided near each end with downwardly projecting studs 27^b having foot flanges 27^c which bear up against stops 27^d adjustably fitted in lugs 29^a 40 on the ends of the body member. The guard plate is thus prevented from displacement and may be adjusted to proper position. See 45 Fig. 3.

In operation the structure is securely and snugly fastened to the rail by bolting it through the rail web. Suitable lubricant is supplied to the reservoir 2, some of it filling 50 the charging pot 21, from which the plunger 15 in its normal position is elevated, as seen in Fig. 1. The wheel 18 of the rolling stock rides up on the guard plate 27 and its tread 17 runs down the plunger head 14. The 55 plunger is thus depressed into the pot 21 and the lubricant therein is forced out in a pre-determined charge, controlled by the by-pass 13^a, through the several ducts and delivered by the nozzle 11 upon the surface or surfaces 60 desired, and is spread along the flange or gauge side of the rail head by the wheel flange 19.

The operation is, of course, repeated by the passing of successive wheels, so that the 65 lubrication is very effective.

As the wheel passes from the plunger head 14 the plunger 15 rises from the pot 21 and a fresh charge of lubricant enters said pot.

In Fig. 4 we show a modification of the device for lubricating the gauge side of a 70 girder rail 30 where interference with motor cars is not to be feared. In this form, the chambered body member 31 is bolted to the rail web as heretofore described. Said member is provided with the charging pot 32 as 75 in the previous form of the device, and a plunger 33 operates in said pot. The plunger has a head 34 guided in a member 35, and is controlled by a spring 36, its upper limit being defined by a stop 37.

80 The head 34 of the plunger plays through an opening in the rail 30 and normally lies high enough to be run down by the flange 38 of the wheel 39.

The essential modification herein lies in 85 the fact that the plunger is provided with a through duct 40 which receives at its lower end the lubricant from the pot 32 and delivers it through its head 34 upon the surface 90 or surfaces to be lubricated.

Though the pressure of the passing wheel 95 may be communicated to the plunger head indirectly through the guard plate 27, we prefer the direct pressure here shown, for the sake of a quick operation, rather than a gradual one, thus insuring a positive and sudden jet of the lubricant with no tendency to back suction of the more or less viscid grease.

100 We claim:—

1. A track-rail lubricator comprising a chambered body-member for a lubricant supply; said member having within it an open charge-pot; a plunger operable by a passing wheel and adapted to enter and to withdraw from said charge-pot for forcing lubricant therefrom; and means for conducting the forced lubricant to the desired surface of the rail head.

105 2. A track-rail lubricator comprising a chambered body-member for a lubricant supply, said member having within it an open charge-pot; a reciprocative plunger operable by the tread of a passing wheel and adapted to enter and to withdraw from said charge-pot for forcing a charge of lubricant from said pot; and means for conducting said charge to the desired surface of the rail head.

110 3. A track-rail lubricator comprising a chambered body-member for a lubricant supply, said member having within it an open charge-pot; a reciprocative plunger operable by the tread of a passing wheel 115 and adapted to enter and to withdraw from said charge-pot for forcing a charge of lubricant from said pot; a nozzle member positioned to deliver the lubricant to the surface of the gauge side of the rail head 120

and ducts to convey the lubricant to said nozzle member.

4. A track-rail lubricator comprising a chambered body-member for a lubricant supply, said member having within it a charge-pot; means for fitting said body member to the track-rail; a reciprocative plunger operable by a passing wheel for forcing a charge of lubricant from said pot; a nozzle member positioned to deliver the lubricant to the desired surface; ducts to convey the lubricant to said nozzle member; and a by-pass controlled by said plunger, leading from said ducts back into the chambered body member for defining said lubricant charge.

5. A track-rail lubricator comprising a chambered body-member for a lubricant supply, said member having a bolt passing through the web of the rail for securing said member to the rail; a plunger operable by a passing wheel for forcing lubricant from said body member; and a nozzle member carried by the securing bolt of said body member positioned to deliver lubricant to the surface of the gauge side of the rail head, said body member and securing bolt having ducts for leading the lubricant to the nozzle member.

30 6. A track-rail lubricator comprising a chambered body-member for a lubricant supply, said member having a bolt passing through the web of the rail for securing said member to the rail; a plunger operable by a passing wheel for forcing lubricant from said body member; a nozzle member carried by said securing bolt positioned to deliver lubricant to the surface of the gauge side of the rail head; and a bushing to seat 40 said nozzle member, said body member, securing bolt and bushing having ducts for leading the lubricant to the nozzle member.

7. A track-rail lubricator comprising a chambered body member for a lubricant supply; a reciprocative plunger associated with said body member for forcing lubricant therefrom, said plunger having a head exposed to the contact of the tread of a passing wheel whereby said plunger is operated; 50 a yieldable guard plate adjacent the plunger head and lying in the path of the wheel tread to receive the initial wheel contact; and means for conducting the forced lubricant to the surface of the gauge side of the rail head.

8. A track-rail lubricator comprising a chambered body member for a lubricant supply; means operable by a passing wheel to force the lubricant from the chambered member; a nozzle member to receive and deliver the forced lubricant; and a shield plate associated with said nozzle member in position for directing the discharged lubricant to the surface of the gauge side of the rail head.

9. A track-rail lubricator comprising a chambered body member for a lubricant supply; means operable by the tread of a passing wheel to force the lubricant from the chambered member; a nozzle member to receive and deliver the forced lubricant; and a shield plate associated with said nozzle member in position adjacent the gauge side of the rail head, for directing the discharged lubricant upon the surface of said side.

10. A track rail lubricator comprising a source of lubricant; a nozzle member; a shield plate associated with said nozzle member and with the rail head in position to receive the lubricant from the nozzle member and deliver it upon the surface of the gauge side of the rail head; and means for supplying said nozzle with the lubricant.

In testimony whereof we have signed our names to this specification.
